WEAR BUSHING STRUCTURE FOR
PERCUSSIVE TOOLSJohn C. Curtis and Elmer G. Gartin, Claremont,
N. H., assignors to Joy Manufacturing Com-
pany, a corporation of Pennsylvania

Application August 14, 1947, Serial No. 768,546

12 Claims. (Cl. 121—32)

1

This invention relates to fluid operated tools and more particularly to improvements in the wear bushing structure of a percussive tool, such as a hammer rock drill.

In fluid operated tools, such as hammer rock drills, considerable wear occurs between the piston striking bar and the front buffer ring and between the cylinder and the rotating chuck sleeve of the drill chuck mechanism. In known constructions, a wear bushing has been inserted in the bore of the front buffer ring to reduce wear, but considerable difficulty has been encountered in holding this bushing in place while still enabling ready replacement thereof when desired. The present invention contemplates improvements over such known constructions in that an improved wear bushing arrangement is provided for the front buffer ring and the cylinder, substantially to reduce wear. The bushing structure of the present invention embodies a wear bushing inserted in the bore of the front buffer ring and a cylinder wear bushing for the rotatable chuck sleeve wherein the cylinder bushing is so arranged and so coacts with the buffer ring bushing as to lock the latter in place. Upon disassembly of the rock drill, the buffer ring bushing may be readily replaced, and, conversely, the parts may be readily assembled. The structure is simple in design and relatively rugged, well adapted to meet the demands of service.

An object of the present invention is to provide an improved wear bushing structure for a fluid operated tool. Another object is to provide an improved wear bushing arrangement for the front buffer ring and cylinder of a hammer rock drill whereby wear of relatively costly parts is substantially reduced. A further object is to provide an improved wear bushing structure wherein one bushing is so arranged and so coacts with the other bushing to lock the latter in its operative position. Yet another object is to provide an improved wear bushing arrangement whereby the piston striking bar and rotatable chuck sleeve are supported and guided in an improved manner. Other objects and advantages of the invention will, however, hereinafter more fully appear.

In the accompanying drawing there is shown for purposes of illustration one form which the invention may assume in practice.

2

In this drawing:

Fig. 1 is a view in central longitudinal section through a hammer rock drill in which an illustrative form of the invention is embodied.

Fig. 2 is a perspective view, partially in section, illustrating the front cylinder bushing.

Fig. 3 is a perspective view of the buffer ring bushing.

Fig. 4 is a cross-sectional view taken substantially on line 4—4 of Fig. 1.

In this illustrative embodiment of the invention, the improved wear bushing structure is embodied in a fluid operated tool, herein a hammer rock drill, comprising a motor cylinder 1 having a bore 2 containing a reciprocatory hammer piston 3. The hammer piston has a piston head 4 fitting the cylinder bore and an elongated reduced cylindrical front extension or striking bar 5 for delivering impact blows to the shank 6 of a working implement 7, herein a conventional lugged rock drill steel. Suitably attached to the front end of the motor cylinder is a chuck housing 8 having a bore 9 in which a chuck sleeve 10 is rotatably mounted, and carried within and 15 rotatable with this chuck sleeve is a chuck bushing 11 for receiving and supporting the lugged shank 6 of the drill steel. Suitably coupled at 12, as by interlocking jaws, to the front end of and rotatable with the chuck sleeve 10 is a driver 20 member 13 within which the steel shank is suitably locked and provided with usual drive lugs 25 engaging the lugs of the steel shank for rotating the steel with the chuck sleeve, all in a conventional manner. The driver member 13 is rotatably mounted in a sleeve-like wear bushing 14 supported within the forward portion of the chuck housing bore. Secured within a bore 15 aligned with the cylinder bore 2 is a front buffer ring or front cylinder head 16, while arranged in 30 a rearwardly located bore 17, likewise aligned with the cylinder bore, is a rear cylinder head or rear head plate 18. A conventional automatic fluid distributing valve mechanism 19, arranged rearwardly of and associated with the rear head plate, serves to control the flow of motive fluid from a suitable supply connection 20 to the opposite ends of the cylinder bore 2 for effecting reciprocation of the hammer piston. A spirally 35 grooved rifle bar 21 is suitably slidably interlocked within the hammer piston and is con-

nected to a ratchet and pawl device 22 which serves to hold the rifle bar against rotation in one direction while permitting free bar rotation in the opposite direction. As the hammer piston moves rearwardly, the rifle bar is held against rotation by the ratchet and pawl device, thereby to effect rotation of the piston, and as the piston moves forwardly, the ratchet and pawl device slips to permit free rotation of the rifle bar, thereby enabling the piston bar to strike an unimpeded blow against the piston shank. Rotation of the piston is transmitted to the drill steel through straight grooves 23 on the piston striking bar 5 slidably interlocked with straight lugs on a chuck nut 24 fixed to the chuck sleeve 10. Thus, as the hammer piston reciprocates to actuate percussively the drill steel, the latter is intermittently rotated, likewise all in a conventional manner.

As is usual in hammer rock drills of the type disclosed, encircling the front buffer ring 16 is an annular lubricant reservoir 25 provided with a suitable filler plug 26 (Fig. 4) and containing a suitable lubricant. Passage means 27 conducts fluid under pressure from the fluid supply connection 20 to the lubricant reservoir, and passage means 28 conducts lubricant from the reservoir to the rotating chuck parts in a well known manner. When the pressure in the passage means 28 is reduced, the pressure in the reservoir, acting on the lubricant therein, forces some lubricant from the reservoir and through the passage means 28 to the parts to be lubricated, in a well known manner.

Now referring to the improved wear bushing structure, it will be observed that fitted in a bore 29 in the front buffer ring or front head 16 is a wear bushing 30 (Fig. 3) in which the piston striking bar or front piston extension 5 is slidably guided. This bushing is of sleeve-like form and engages, at its rear end, a forwardly facing shoulder 31 on the buffer ring. Arranged in a front bore 32 in the cylinder is a wear bushing 33 (Fig. 2) having an inwardly directed circular flange 34 surrounding the circular front reduced end 35 of the wear bushing 30, as shown in Fig. 1. The rear surface of the flange 34 engages a forwardly facing shoulder 36 on the bushing 30 for locking the latter in place within the bore of the buffer ring. The rear end of the chuck sleeve is journaled in the bushing 33 in the manner shown. Thus the wear bushing 30 reduces wear of the buffer ring while the bushing 33 reduces wear of the cylinder, and the bushings are so arranged and constructed and so coat with one another that the cylinder bushing 33 locks the bushing 30 in place.

When the front chuck housing 8 is suitably detached from the cylinder, it may be removed, together with the chuck parts contained therein, forwardly from the cylinder, and during such forward movement, the lugs of the chuck nut 24 slide forwardly from the straight grooves 23 on the piston striking bar in an obvious manner. The cylinder bushing 33 remains in the position shown in Fig. 1 upon removal of the front chuck structure. The back head structure, including the rear head plate and distributing valve mechanism, may then be suitably detached from the rear cylinder. The front buffer ring has a tight press fit within the cylinder bore 15, and when the rear head structure is detached, the buffer ring, together with the wear bushing 30, may be forced rearwardly from the bore 15; and upon removal of the buffer ring, the wear bushing may

be readily replaced when worn. In the event the cylinder bushing 33 becomes worn, it may at that time also be readily replaced. The front chuck structure and the rear head structure may then be reassembled with respect to the cylinder, again bringing the bushings 30 and 33 together as shown in Fig. 1, with the front cylinder bushing locking the buffer ring bushing in place.

As a result of this invention, it will be noted that an improved wear bushing structure is provided whereby wear of relatively costly parts necessitating replacement thereof is substantially reduced. By arranging the bushings in the novel manner disclosed, with the front cylinder bushing coaxing with the buffer ring bushing, the latter is firmly locked in place within the front buffer ring. Due to the improved bushing arrangement disclosed, the bushings may be readily replaced when worn upon disassembly of the drill. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What we claim as new and desire to secure by Letters Patent is:

1. In a percussive tool comprising a cylinder having a bore, a piston reciprocable in said bore and having a reduced forward extension, a front buffer ring, a chuck housing secured to said cylinder and a rotatable chuck sleeve mounted in said chuck housing and projecting rearwardly into said cylinder, the improvement consisting of a replaceable wear bushing fitted in said front buffer ring for guiding said piston extension and removable axially forwardly from said ring, and a replaceable cylinder wear bushing in which the rearward portion of said chuck sleeve is received and rotatably mounted, said cylinder bushing arranged coaxial with said buffer ring bushing at the forward side of the latter and coaxing with said buffer ring bushing to hold the latter against forward axial displacement from said buffer ring.
2. In a percussive tool comprising a cylinder having a bore, a piston reciprocable in said bore and having a reduced forward extension, a front buffer ring, a chuck housing secured to said cylinder and a rotatable chuck sleeve mounted in said chuck housing and projecting rearwardly into said cylinder, the improvement consisting of a replaceable wear bushing fitted in said front buffer ring for guiding said piston extension and removable axially forwardly from said ring, said buffer ring bushing having a reduced forward cylindrical portion providing a forwardly facing shoulder, and a replaceable cylinder wear bushing in which the rearward portion of said chuck sleeve is received and rotatably mounted, said cylinder wear bushing arranged coaxial with said buffer ring bushing at the forward side of the latter and having an inwardly directed rear annular flange surrounding said reduced forward portion of said buffer ring bushing, and the rear surface of said flange abutting said shoulder to hold said buffer ring bushing against forward axial displacement from said buffer ring.
3. In a fluid operated tool comprising a cylinder having a bore, a piston reciprocable in said bore, a front buffer ring, a chuck housing secured to

the front end of said cylinder and a rotatable chuck part mounted in said chuck housing and projecting rearwardly into said cylinder, the improvement consisting of a replaceable sleeve-like wear bushing fitted in said buffer ring for slidably guiding said piston and a replaceable cylinder wear bushing in which the rearward portion of said chuck part is received and rotatably mounted, said cylinder wear bushing arranged coaxial with said buffer ring bushing and having a portion coacting with said buffer ring bushing for locking the latter against forward axial displacement from said buffer ring.

4. In a fluid operated tool comprising a motor having relatively reciprocable motor parts and a rotatable tool chuck, the improvement consisting of a replaceable wear bushing arranged with respect to one motor part in a position to guide the reciprocable motor part, and a replaceable wear bushing positioned with respect to said one motor part rotatably to receive and support said rotatable chuck part, said bushings arranged in coaxial relation and having coacting portions so that one bushing serves to lock the other against axial displacement.

5. In a fluid operated tool comprising a motor having relatively movable motor parts and a chuck mechanism including a rotatable chuck part, the improvement consisting of separate replaceable wear bushings for guiding the reciprocable one of said motor parts and said rotatable chuck part respectively, said chuck part being received and mounted in its bushing, said bushings arranged in coaxial relation and having coacting portions so that one bushing serves to hold the other against axial displacement.

6. In a fluid operated tool comprising a motor having relatively movable motor parts and a chuck mechanism including a rotatable chuck part, the improvement consisting of separate replaceable wear bushings for guiding the movable one of said motor parts and said rotatable chuck part respectively, said chuck part being received and mounted in its bushing, said bushings arranged in coaxial relation and having coacting portions one abutting the other so that one bushing serves to hold the other against axial displacement.

7. In a fluid operated tool, the combination comprising relatively movable parts, one of which is reciprocable and the other rotatable, and a supporting and wear bushing structure comprising a support having a replaceable sleeve-like wear bushing supported axially therein for guiding the reciprocable part, and a support having a coacting replaceable front wear bushing axially supported therein and in which the rotatable part is received and rotatably mounted, said sleeve-like wear bushing having a reduced forward end providing a forwardly facing shoulder, and said coacting front bushing having an inwardly directed circular flange surrounding said reduced forward end with its rear surface abutting said forwardly facing shoulder for holding said sleeve-like bushing against forward axial displacement from its support.

8. In a tool of the character disclosed, the combination with relatively movable tool parts one of which is reciprocable and the other rotatable, of a supporting and wear bushing structure comprising a support having a replaceable sleeve-like wear bushing axially supported therein for guiding the reciprocable part, and a support having a replaceable annular wear bushing axially supported therein in which the rotatable part is

received and rotatably mounted for providing a bearing for the rotatable part, said annular wear bushing abutting said sleeve-like wear bushing to hold the latter against axial displacement from its support.

9. In a fluid operated tool comprising a motor having relatively reciprocable motor parts and a chuck mechanism including a rotatable chuck part, the improvement consisting of separate replaceable wear bushings for guiding the reciprocable one of said motor parts and said rotatable chuck part respectively, said chuck part being received and mounted in its bushing, said bushings arranged in coaxial relation and having coacting portions in abutting relation and said portion of said bushing for said rotatable chuck part serving to hold said other bushing against forward axial displacement.

10. In a tool of the character disclosed, the combination with relatively movable tool parts one reciprocable and the other rotatable, of a wear bushing structure comprising a replaceable sleeve-like wear bushing for guiding the reciprocable motor part and a replaceable annular wear bushing coaxial with said sleeve-like bushing and in which said rotatable tool part is received and mounted for rotation, said annular bushing having a rear annular flange abutting a portion of said sleeve-like bushing to maintain the latter against forward axial displacement.

11. In a tool of the character disclosed, the combination with relatively movable tool parts one reciprocable and the other rotatable, of a replaceable wear bushing structure comprising a sleeve-like wear bushing for guiding the reciprocable motor part and having a reduced forward portion providing a forwardly facing shoulder, and a replaceable annular wear bushing in which said rotatable motor part is received and mounted for rotation, said bushings arranged in coaxial relation and said annular wear bushing having an inwardly directed rear flange surrounding said reduced portion and abutting said shoulder for maintaining said sleeve-like bushing against forward axial displacement.

12. In a percussive tool comprising a cylinder having a bore, a piston reciprocable in said bore and having a reduced cylindrical forward extension, a front buffer ring having a bore provided with a forwardly facing annular rear end wall, a chuck housing secured to said cylinder and a rotatable chuck sleeve mounted in said chuck housing and projecting rearwardly into said cylinder, the improvement consisting of a replaceable sleeve-like wear bushing fitted in the bore of said front buffer ring with its rear end in abutting engagement with said annular rear end wall for guiding said piston extension, said bushing having a reduced forward portion providing a forwardly facing shoulder and removable forwardly from said buffer ring bore, and a replaceable cylinder wear bushing arranged coaxially with said sleeve-like bushing and in which the rearward portion of said chuck sleeve is received and rotatably mounted, said cylinder bushing arranged at the forward side of said buffer ring bushing and having an inwardly directed rear annular flange surrounding said reduced forward portion of said buffer ring bushing and the rear surface of said flange abutting said shoulder to hold said buffer ring bushing against forward axial displacement from the bore of said buffer ring.
